[57] **CLAIM**

The ornamental design for set of side storage compartments for an automotive van, as shown and described.

DESCRIPTION

FIG. 1 is an end elevation view of a set of side storage compartments for an automotive van showing my new design;

FIG. 2 is a front elevation view of one of the side storage compartments of the set shown in position of use on an automotive van;

FIG. 3 is an end elevation view thereof opposite to that shown in FIG. 1;

FIG. 4 is a front elevation view of the second side storage compartment of the set shown in position of use on an automotive van;

FIG. 5 is a top plan view of the set of side storage compartments in position of use on an automotive van;

FIG. 6 is a rear elevation view of the side storage compartment shown in FIG. 2; and,

FIG. 7 is a rear elevation view of the side storage compartment shown in FIG. 4.

The broken line showing of an automotive van in FIGS. 2, 4 and 5 of the drawing is for illustrative purposes only and forms no part of the claimed design.
